United States Patent Office.

GEORGE L. WITSIL, OF PHILADELPHIA, PENNSYLVANIA, ASSIGNOR TO HIMSELF AND CHARLES MERRILL, OF DETROIT, MICHIGAN.

Letters Patent No. 97,018, dated November 16, 1869.

IMPROVED WASHING-MACHINE.

The Schedule referred to in these Letters Patent and making part of the same

I, GEORGE L. WITSIL, of the city and county of Philadelphia, and State of Pennsylvania, have invented certain Improvements in Washing-Machines, of which the following is a specification, reference being had to the annexed drawings, being a part thereof.

This invention relates to washing-machines for washing clothing of various kinds, wool, rags, and other material; and

It consists in the combination and arrangement of the parts of which the machine is composed.

Figure 1 is a view, partly in section and partly in elevation, of my improved washing-machine.

Figure 2 is a vertical sectional elevation, showing an end view of the agitator, and a side view of two of the perforated diaphragms.

Figure 3 is a vertical central section, showing the agitator, case, or tub, and the hollow journal, for the escape of steam from the machine.

Figure 4 is a plan or top view, showing the position of the perforated diaphragms, the agitator, the hollow journal, and the bearing or support for the same.

Corresponding letters refer to corresponding parts in the several figures.

A, in the drawings, represents a tub or vessel, which may be of wood; hooped with iron, or it may be of any other suitable material, and of any capacity, to hold the required amount of material to be cleansed. For convenience in using it should be open at its upper end, but should be supplied with a close-fitting cover, A', to be used when the cleansing-process is being performed, but which may be readily removed when such process is completed, so as to permit free access to the contents of the vessel, as well as to the machinery contained therein.

B B represent perforated diaphragms or plates, which are to be secured within the vessel A, in such a manner as that their inner sides shall present an angle to each other, substantially as shown in fig. 4 of the drawings, and thus leave a space or chamber between them, for the clothes or other material to be cleansed. It will be seen that the diaphragms or plates extend from the bottom of the vessel to near its top, and that they are perforated for the passage of water from the spaces outside of them.

C represents an agitator, which consists of a thin piece of wood or metal, placed in a vertical position between the parts of the diaphragms, and which has upon its lower edge a journal or pivot, upon which it turns, a step being provided upon the inner surface of the lower head for it to rest in. This agitator extends up nearly to the top of the diaphragms, and has secured to its upper edge a hollow journal, which serves to keep it in its position, and forms the axis upon which it turns.

D represents a hollow journal, which is to be constructed with a flange upon its lower end, for the purpose of securing it to the agitator C. Above this flange the journal is to be made hollow, as shown in the drawings, in order that when the machine is in use, any steam, which may arise from the water, may escape, or any air which may be contained in such vessel may find egress through this opening.

E represents a support or bearing, for the hollow journal D, which consists of a piece of metal or of wood secured to the upper edges of the diaphragms, at or near the point where they come in contact with each other, it having the proper opening in its centre for the passage of such journal.

F represents a cross-bar, which is secured to the upper surface of the cover A', and projects beyond the outer surface of the same for a distance sufficient to enable it to pass under the projecting portions of hooks H, which are secured to the outer surface of the vessel A, in such a manner that when the cover is placed upon such vessel, and partially rotated, the ends of this bar will pass under said hooks, and thus press said cover down upon the edge of the vessel, thereby holding the cover in place, and causing it to form a tight joint with such vessel.

G represents a handle, which is to be placed upon the upper projecting end of the hollow journal, where it may be held by means of a set-screw, or any other suitable devices, so that it can be removed, when it is necessary to remove the cover from the vessel, but so that it will not turn upon said journal, when it is necessary to give motion to the agitator.

The operation of my improved machine is as follows:

The parts, having been constructed and arranged as described, the material to be cleansed is to be placed in the compartments formed by the diaphragms, other than the one occupied by the agitator, when the water and other cleansing-material are to be put into that portion of the machine occupied by the agitator, the cover of the machine placed in position, and the handle secured to the journal, when the agitator is to be oscillated through about one-fourth of a revolution, which will cause the water or other cleansing-material to be forced through the apertures in the diaphragms and amongst the clothes, with great force, thus causing any substance, foreign to such clothes, to be removed therefrom.

When the cleansing-process has been completed, the cover is to be removed and the clothes taken out, when the compartments may be again filled, and the operation repeated.

One important advantage arising from my method of washing clothes is, that they are not pounded, rubbed, or moved while being cleansed, and consequently,

are not worn or otherwise injured, as in the other methods of washing or cleansing.

Having thus described my invention,

What I claim, and desire to secure by Letters Patent, is—

1. The combination and arrangement of the perforated diaphragms, the oscillating agitator, and the enclosing-vessel, substantially as and for the purpose specified.

2. The combination of the oscillating agitator and

the hollow journal, substantially as and for the purpose set forth.

In testimony whereof, I have signed my name to this specification, in the presence of two subscribing witnesses.

GEO. L. WITSIL.

Witnesses:

FRED. KOONES,
A. RUPPERT.
